(57) **CLAIM**

The ornamental design for a helmet visor, as shown and described.

DESCRIPTION

FIG. 1 is a perspective view of a helmet visor showing my new design.

FIG. 2 is a front view of the helmet visor shown in FIG. 1. FIG. 3 is a rear view of the helmet visor shown in FIG. 1. FIG. 4 is a side view of the helmet visor shown in FIG. 1. FIG. 5 is a top view of the helmet visor shown in FIG. 1; and, FIG. 6 is a bottom view of the helmet visor shown in FIG. 1.

The long and short broken lines define the bounds of the claimed design and form no part thereof.

The evenly spaced broken lines show portions of the helmet visor that form no part of the claimed design.
